UNITED STATES PATENT OFFICE.

JOHN LEVEY AND THOMAS SADLER, OF LINDSAY, CANADA.

MARINE-ENGINE GOVERNOR.

SPECIFICATION forming part of Letters Patent No. 701,060, dated May 27, 1902.

Application filed April 17, 1901. Serial No. 56,192. (No model.)

To all whom it may concern:

Be it known that we, JOHN LEVEY and THOMAS SADLER, of the town of Lindsay, in the county of Victoria, Province of Ontario, 5 Canada, have invented certain new and useful Improvements in Marine-Engine Governors, of which the following is a specification.

The object of our invention is to devise a governor for marine engines which will prevent the racing of the engine which takes place when the screw by the pitching of the vessel is either partly or wholly lifted out of the water; and it consists, essentially, of a valve adapted to control the steam-supply to the engine, a pendulum adapted to swing relative to the keel of the vessel in a fore-and-aft plane, and means whereby the relative motion of the pendulum and keel when the vessel pitches and throws the screw to the 15 surface will operate the controlling-valve and wholly or partially shut off the steam from the engine, substantially as hereinafter more specifically described and then definitely claimed.

25 The drawing is a sectional elevation of our governor.

A is a valve-chest provided with the usual steam passages and ports. Within the valve-chest are located the slide-valves B and C. 30 By the motion of either of these valves the ports a may be opened or closed. Hence the valve C will be referred to in the claims as the valve controlling the steam-supply.

D is the valve-rod of the valve B, passing 35 upwardly through the hollow valve-rod E of the slide-valve C. The hollow valve-rod E passes through a suitable stuffing-box in the end of the valve-chest and is secured to the lower end of the frame F. A suitable stuffing-40 box is provided to pack the end of the hollow valve-stem E where the valve-stem D passes out through it. The frame F carries friction-rollers b, which are adapted to engage the end 45 of the lever G, which is forked to permit of its embracing the valve-rod D. As the drawing is a section, only two of the friction-rollers b are seen; but it will be understood that the other half of the frame is provided with similar rollers to engage the other half of the 50 forked end of the lever G. This lever is journaled on the stud c on the frame of the governor. Preferably on the same stud is jour-

naled the pendulum H, preferably provided with the adjustable weight d. A connection is formed between the lever G and the pendulum H by means of the bolts I, which pass through slots e in the lever G and are screwed into the pendulum H. When these bolts are tightened up, a rigid connection is formed between the lever and the pendulum, but owing 55 to the slots e the relative position of the two may be adjusted when desired.

The arm J extends outwardly from the lever G at the opposite side of the stud c from the forked end of the lever. A counterbalancing-weight f is adjustably secured on this arm and serves to balance the weight of the lever G and the slide-valve C.

The lower end of the pendulum H is preferably slotted to embrace the radius-bar K, 70 as shown, and friction-rollers g are pivoted in the end of the pendulum, one on each side of the radius-bar, to reduce the friction. The roller on the near side is the only one visible in the drawing. On the radius-bar we place 75 the stops L, which are slideable thereon and adjustable by set-screws, as shown. Each stop is preferably provided with a rubber buffer h.

As previously described, the valve-rod D 80 extends up through the frame F and is connected with the centrifugal governor M, which is of ordinary construction and is operated by bevel-gearing in the ordinary manner. On the top of the valve-rod D, we place the adjusting-nuts P, which serve to limit the downward motion of the valve B.

Below the lower collar of the centrifugal governor is located the grooved spool N, which is engaged by the end of the counterbalancing-lever O, pivoted on the frame of the machine and provided with the adjustable weight Q. This weight may be adjusted to balance the weight of the valve B and its connected parts.

Under ordinary circumstances the centrifugal governor M will take care of all variations in speed caused by variations in the work being done by the engine. An ordinary governor, however, does not begin to act until 90 the engine has increased its speed. When a vessel plunges and lifts her screw partly or wholly out of water, racing at once commences, and the ordinary governor produces 95 100

no effect until the racing has continued for a sufficient length of time to effect material injury and the waste of a considerable amount of the energy developed by the engine. With 5 our special governor as soon as the vessel plunges and lifts her stern the inertia of the pendulum causes it to swing outwardly on the radius-bar, thus depressing the valve C through its connections with the lever G. 10 The steam may be thus wholly or partly cut off as soon as the screw lifts out of water sufficiently to become dangerous. As it is not desirable that the steam should be reduced in 15 quantity or cut off when ordinary pitching alone takes place, we adjust the sternward stop L forward on the radius-bar a sufficient number of degrees to allow for ordinary pitching. This naturally depresses the valve C and 20 partly closes the port α . To compensate for this, the bolts I may be loosened and the position of the lever G altered to raise the valve clear of the ports. The lever may then be 25 clamped in its new position by retightening the bolts. When this has been done, no movement of the pendulum takes place until the pitch of the vessel exceeds the minimum arranged for by the adjustment of the sternward stop L. As vessels are not always 30 trimmed on an even keel, the adjustments described permit of the governor being corrected to suit whatever trim the vessel may be in. The outer stop L serves to limit the 35 amount of the cut-off. When it is set out at the end of the radius-bar, the pendulum has sufficient range of motion to completely close the ports α . By moving it in, the exact de-

gree of cut-off can be adjusted to suit any condition. The weight on the pendulum is preferably adjustable, as shown, so that its inertia may be regulated as desired to suit the 40 amount of friction in the moving parts that has to be overcome. When we speak of the pendulum swinging, it is of course merely relatively to the other parts, as they actually do the swinging, and the pendulum, owing 45 to the inertia of its weight, always tends to hang with its center of gravity vertically below its point of support.

The apparatus is of course set up with the radius-bar pointing toward the bow of the 50 vessel.

What we claim as our invention is—

In a device of the class described, the combination of a valve-chest provided with a suitable port or ports; two valves sliding therein 55 and each adapted to open and close the said ports; a hollow valve-rod secured to one valve; a valve-rod secured to the other and extending through the hollow valve-rod; an ordinary centrifugal governor connected with one 60 valve-rod; a pendulum adapted to swing relative to the keel of the vessel in a fore-and-aft plane; and means whereby the relative motion of the pendulum and keel when the vessel pitches will operate the last-mentioned 65 valve-rod, substantially as described.

Lindsay, March 30, 1901.

JOHN LEVEY.

THOMAS SADLER.
